CLAIM

We claim the ornamental design for a food processor for
blender assembly, as shown and described.

DESCRIPTION

FIG. 1 is a front top perspective view illustrating a food
processor attachment for a blender assembly of the present
disclosure;

FIG. 2 is a rear top perspective view of the food processor
of FIG. 1;

FIG. 3 is a front elevational view of the food processor of
FIG. 1;

FIG. 4 is a rear elevational view of the food processor of
FIG. 1;

FIG. 5 is a first side elevational view of the food processor
of FIG. 1;

FIG. 6 is a second side elevational view of the food
processor of FIG. 1;

FIG. 7 is a top plan view of the food processor of FIG. 1;
and,

FIG. 8 is a bottom plan view of the food processor of FIG.
1.

The broken lines depict portions of the article that form no
part of the claimed design.

1 Claim, 8 Drawing Sheets
